Inventor

Attorney

UNITED STATES PATENT OFFICE.

JOHN W. GUNN, OF RIVERDALE, MARYLAND.

SLIP JOINT.

Application filed February 11, 1926. Serial No. 87,559.

In plumbing work, and particularly flush tank and bowl connections, it frequently happens that the pipes or parts to be connected and sealed against leakage do not properly align, and in forcing alignment, as is sometimes done, injury to the tank and bowl connections often occurs. By reason of the fact that the piping associated with such structures is usually of frail character, forcing the same into proper alignment and connection increases the hazard of injury thereto as well as subsequent leakage or breakage. Again, in repair work where it becomes necessary to remove the bowl, it has heretofore been necessary to shut off the water supply and drain the system preliminary to dismantling the fixtures. This dismantling work includes disconnection of the pipes between the tank and bowl with the risk of breaking the same and managing the bowl bib and flush tank connection, and frequently it is required that the flush tank itself be taken down. The work and expense incident to these operations are at once apparent.

It is the primary object of the present invention to provide means whereby the flush water connection between the tank and bowl may be readily and effectively made notwithstanding that the bowl and tank connection may not be in true alignment. The invention further contemplates means whereby the bowl may be removed wholly independent of the tank, not requiring shutting off of the water supply or even draining the flush tank, and not requiring disconnection of the water supply pipe leading to the tank or danger of injury either to this connection or the flush water pipe connection at its introduction to the tank.

The invention further contemplates the employment of a slip-joint, by the use of which plumbing fixtures such as referred to may be readily installed with a minimum of effort and at a great saving of time, and wherein proper sealed joints in the pipe connections are assured. It is further contemplated that with the use of the invention as hereinafter set forth, the repair work may be quickly and effectively carried out at a great saving of work, time and material and without the exercise of skill not ordinarily possessed by the average plumbing mechanic.

With these objects in view, together with others which will appear as the description proceeds, the invention consists in the novel

construction, combination and arrangements of parts, all as will be described more fully hereinafter, illustrated in the drawings and particularly pointed out in the claims.

Fig. 1 is a side elevation illustrating a connection between a flush bowl and tank, wherein a slip joint involving the present invention is employed.

Fig. 2 is a longitudinal sectional view taken through the piping constituting the connection, and

Fig. 3 is a transverse sectional view taken substantially upon line 3—3 of Fig. 2.

As stated heretofore, the primary adaptation of the invention is in the connection between the flush tank and the bowl, and as it will be understood that various types of bowls and tanks are employed, the invention is equally adaptable to one as to the other of such types. Furthermore, it will be comprehended from the following that the invention may with equal facility and efficiency be employed in other pipe and tube connections.

In the drawing, 4 represents the lower end of a conventional type of "low down" flush tank, while 5 indicates a portion of the bowl in connection with the same. The tank 4 has connected with its lower end the usual flush water discharge pipe represented at 6, the latter having a right angular bend 7 near its lower end which is to be brought into communication with the interior of the bowl 5. To this end, the bowl 5 has anchored or in any preferred manner secured therein a connector in the form of a spud represented at 8. These spuds may take any one of a number of forms, the present illustration being conventional. These spuds are secured in water tight connection at their inner ends within the porcelain bowl 5, while their outer extremities are threaded externally for the accommodation of a packing nut represented at 9.

Ordinarily, the lower end of the tube or pipe 6 is inserted within the outer portion of the spud 8, and the nut 9 is then tightened so as to pack the joint in a water tight connection. As has heretofore been stated there are many objections to this manner of establishing the connection.

In carrying out the invention, the spud 8 is coupled to the lower end of the pipe 6 by means of a connecting tube or pipe indicated at 10. This pipe is of a similar diameter to the pipe 6 and the interior of

the spud 8, and is preferably of a metal corresponding in thickness and finish with the down pipe 6. The tube 10 may be of any desired length, and may be furnished in 5 certain prescribed sizes to be cut off if desired to adapt the same to a specific job of work. The outer extremity of the coupling pipe 10 is flared slightly so as to receive the lower end of pipe 6 in comparative snug 10 engagement, and the outer surface of the pipe 10 at this enlarged part is threaded as at 11 for the accommodation of the threads of a conventional type of packing nut indicated at 12. This nut is of standard size and 15 construction, and is similar in all respects to the nut 9. To facilitate manipulation of the parts in applying or detaching the connector 10, the exterior surface of the said connector may be made square or hexagonal 20 as indicated at 13 for application of a wrench thereto.

With the use of a connector of this character, it is at once apparent that a union of the pipe 6 with the bib 8 may readily be 25 made notwithstanding that the bowl and tank may be further apart than the standard fittings would permit of connecting. Furthermore, the angular lower end of the tube 6 may not be in exact alignment with 30 the bib, and yet with the present connector a union of these parts may be readily established without straining, distorting or twisting either the down pipe or the bib. When it is desired to connect the parts, the smaller 35 end of the connecting tube 10 is inserted in the bib while the outer or larger end encloses the angular end of the down pipe 6. With the parts thus assembled, the packing nuts 9 and 12 are tightened, so that a secure and 40 water tight connection is established between the bib and the down pipe. Any unevenness or irregularity will be compensated for in 45 this connection without damage, injury or strain upon any of the standard parts. It will be understood, of course, that flush 50 water pipes of this connection are ordinarily of frail structure, precluding material bending or twisting without danger of breakage or cracking of the pipes or injury to the connections thereof.

It will be noted that the flared portion of the outer end of the connector 10 is of appreciable depth. This is to permit of the 55 said end being slid longitudinally of the lower end of pipe 6 to permit of easy adjustment in assembling the device as well as in detaching operations. In making the detachment, the packing nuts 9—12 are first loosened, and may be backed until off the

threads of the parts with which they co-operate. The connector 10 may then easily be slid outwardly so that its inner end becomes disengaged from within the bib 8. This sliding movement is permitted by the depth of the flared portion at the outer 65 end of the tubular connector. It is obvious, therefore, that assemblage and dismantling of the parts may be readily carried out without in any way straining or forcing either the bib or the water pipe 6.

While the above is a description of the invention in its preferred embodiment, it will be understood that variations in the minor details of construction, assemblage and arrangement of parts may be resorted to 70 without departing from the spirit of the invention as defined by the claims.

Having thus described my invention, I claim:

1. The combination with a pipe end and 80 a bib in fixed position relative to each other; of a connector comprising a tubular member of exterior diameter for the greater part of its length corresponding to the interior diameter of the bib and adapted to engage 85 within the latter, the opposite end of the said tubular member being enlarged, inwardly from its extremity a depth greater than the extent to which the first mentioned end of the tubular member extends within 90 the bib, the said enlarged end adapted to fit over and snugly engage the said pipe, and packing nuts for connecting the said ends to the bib and pipe respectively.

2. In combination, a water supply pipe 95 having a smooth exterior surface at one end and a bib having a smooth internal surface, and threads upon its exterior surface; said pipe and bib being fixed relative to each other, a connector comprising a tubular 100 member of exterior diameter for the greater part of its length corresponding to the internal diameter of the bib and adapted for sliding fit within the same, the opposite 105 end of said connector enlarged upon its interior surface to correspond with the external diameter of said water supply pipe and adapted to slidingly receive said pipe, the said internal enlargement of said connector 110 being of greater length than the extent to which the first mentioned end of the connector extends within the bib, threads upon the exterior of said enlarged end of the connector, and packing nuts engaged with the threads of said bib and said enlarged end 115 of the connector.

In testimony whereof I affix my signature.
JOHN W. GUNN.
